L. F. TURNBULL
GROMMET TOWEL HOLDER

Filed Oct. 14, 1922

Inventor
Leroy Frederick Turnbull

UNITED STATES PATENT OFFICE.

LEROY FREDRICK TURNBULL, OF ST. LOUIS, MISSOURI.

GROMMET TOWEL HOLDER.

Application filed October 14, 1922. Serial No. 594,668.

To all whom it may concern:

Be it known that I, LEROY F. TURNBULL, a citizen of the United States, and resident of St. Louis, Missouri, have invented certain new and useful Improvements in a Grommet Towel Holder, of which the following is a specification.

This invention relates to improvements in a grommet towel holder, and has for its object a frame by which a determined number of towels are clamped together for the purpose of delivering said towels to an individual towel holder or cabinet, and by means of the same the quantity of towels so delivered are of accurate amount and much more readily and easily applied to the cabinet, this dispensing with the necessity of counting and handling each towel separately.

20 A further object of my invention is to construct a frame which is used in conjunction with laundering towels and after the same have been ironed each towel by means of its grommet is placed over the supporting post and when said post is filled a certain number of towels is mounted thereon and the frame is then folded over the bundle and fastened to the post and in this manner the laundered towels are delivered to the individual towel cabinet.

Figure 1, is a perspective view of my invention shown in extended position ready for the application of the laundered towels. Fig. 2, is a perspective view of my invention when in folded position. Fig. 3, is a perspective view of my invention showing the same equipped with a determined number of towels and in position ready for delivery.

40 Fig. 4, is a detail sectional view of the upper portion of the standard or supporting post showing the attaching means.

Fig. 5, is a detail sectional view of the upper portion of the standard or supporting post showing the application of a towel guide point and towel grommet in a position ready to be applied on said post.

Fig. 6, is a detail perspective view of a modified form of post.

50 In the general construction of my invention I provide a suitable frame consisting of a base section 7, a rear section 8 and a top section 9. In the front of the base section 7 is rigidly mounted a standard or towel supporting post 10, its upper portion provided with a hole or bore 11 in which is adapted to

be inserted the projection 12 formed on the front end of the top section 9 when said section is folded in a position as shown in Fig. 2.

60

The rear section 8 is hingedly connected to the rear end of the base section, and the top section 9 is hingedly connected to the top of the rear section 8.

In applying the towels to the holder the frame is laid out in extended flat position as shown in Fig. 1, with the towel post 10 in proper position so that the towels 12', each of which is provided with a grommet 13 can be readily and easily applied over the post 70 when said towel is removed from the mangle or ironing machine.

In applying the towels to the holder the frame is laid out in extended flat position as shown in Fig. 1, with the towel post 10 in proper position so that the towels 12', each of which is provided with a grommet 13 can be readily and easily applied over the post 70 when said towel is removed from the mangle or ironing machine.

This device is used for individual towels and the operator when grasping each towel as they come from the machine places the 75 same in folded position over the supporting post and when the towels pile-up so that the top one is in a position directly beneath the opening 11, the operator instantly knows that a given number, for example 50 towels, 80 are on the post. Then the remainder of the frame is folded up in a position as shown in Fig. 3, and the projection 12 inserted in the opening 11; this bundle is then ready for delivery and the delivery-man knows that 85 when delivering the bundle of towels to the individual towel rack, that fifty towels have been placed on the rack and a charge for that number is then made.

During the application of the towels over 90 the post a guide plug 14 is placed in the top post so that the towels are readily and easily guided in position without any particular effort, and when the number of towels are in position this plug is removed and placed 95 on the next holder to be equipped with the like number of towels.

In some instances I may construct the post in the form as shown in Fig. 6, that is, by constructing the same out of wire 100 15 which would be a continuation of the frame, but I find for practice that the hollow column 10 is most preferable as the same corresponds with the end of the individual rack and by placing the end against 105 the same the entire bundle of towels can be shoved from the post on to the rack without handling each towel separately.

After the bundle has been placed on the rack the holder is returned to the laundry 110 and re-used. It is as much a convenience to the laundry as to the delivery-man as well

as preventing the counting of the towels.

Having fully described my invention what I claim is:

- 5 1. A grommet towel holder comprising a foldable frame, a towel supporting member carried by said foldable frame and a means for holding the towels in position on said supporting member, substantially as specified.
- 10 2. A grommet towel holder comprising a towel supporting upright, a base supporting said upright, a swinging frame attached to said base, and a means for attaching the frame to the upper part of the upright, substantially as specified.
- 15 3. A device of the class described comprising a standard, a base, a hinged rear section, a hinged top section, all arranged to be folded around a stack of towels and a means carried by the top section by which it is detachably connected to the upper end of the standard, substantially as specified.
- 20 4. A device of the character described comprising a towel supporting standard, a base radiating therefrom, a rear section movably attached to said base, a top section movably attached to the rear section, and a projection formed on the top section

to be inserted in a hole formed in the standard, the entire mechanism supporting a determined number of towels for delivery to individual towel racks, substantially as specified.

30 5. A grommet towel holder for delivery of towels to individual towel racks comprising a frame constructed in movable sections, a towel supporting standard rigidly located on said frame, said frame adapted to encircle the bundle of towels for delivery purposes, substantially as specified.

35 6. A grommet towel holder comprising a frame of skeleton formation, said frame consisting of a base section; a movably attached rear section; a movably attached top section; a towel supporting post over which the grommet ends of the towels are placed; and a fastening means for connecting the top section to the post, substantially as specified.

40 45 In testimony whereof, I have signed my name to this specification, in presence of two subscribing witnesses.

LEROY FREDRICK TURNBULL.
